UNITED STATES PATENT OFFICE.

LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

FLUID-OPERATED PERCUSSIVE TOOL.

1,258,855.

Specification of Letters Patent. Patented Mar. 12, 1918.

Application filed December 31, 1914. Serial No. 879,881.

To all whom it may concern:

Be it known that I, LEWIS C. BAYLES, a citizen of the United States, residing at Easton, in the county of Northampton and State 5 of Pennsylvania, have invented a certain new and useful Improvement in Fluid-Operated Percussive Tools, of which the following is a specification.

This invention relates to fluid operated 10 percussive tools, and more particularly to tools of the type wherein the admission of fluid to opposite ends of the cylinder is controlled solely by the movement of the piston, without the use of intermediate valve 15 mechanism.

The object of this invention is to provide 20 a tool of this type in which the full pressure areas of the piston are alternately exposed to live fluid pressure, and the excessive weight of piston and leakage eliminated, which have heretofore been unavoidable in tools of this type, such as shown, for instance, in the patent to Keller, No. 549,514, dated November 12th, 1895.

25 This object is accomplished by the invention, practical embodiments of which are shown in the accompanying drawings, in which—

Figure 1 shows a diagrammatic longitudinal section of a tool embodying my invention while

Fig. 2 shows a similar section of a modification in which the inlet arrangement is the same, the exhaust mechanism being somewhat modified.

The tool, as shown in Fig. 1, comprises a cylinder 1, with a bore of two diameters, a larger forward bore 2, and a smaller rearward bore 3. In the cylinder slides a piston having a head 4 fitting the larger forward bore 2, and a shank 5 fitting the smaller rearward bore 3, the shank 5 having two depressions or necks, a forward neck 6, close to the piston, and a rearward neck 7 near the rearward end of the shank. Fluid is admitted to the cylinder through an inlet passage 8 which opens into the side of the small bore 3 near its forward end. The neck 6 is so placed, and is of such length, that when the piston is in the position shown in Fig. 1, fluid will be admitted into the rear end of the bore 2 past the neck 6 and also through a passage 9 which affords constant communication between the rearward end of the bore 2 and the rearward end of bore 3, so that when

the piston is in the position shown in Fig. 1 there is live pressure both on the rear face of the piston head 4 and on the rear face of the shank 5, and thus is exerted on the full effective rear pressure surface of the piston. 60 To admit fluid to the forward end of the bore 2 a port 10 is provided in the side of the bore 3 somewhat rearward of the passage 8, and a passage 11 leads from the port 10 from the forward end of the bore 2. This 65 port 10 is put into communication with the rearward passage 8 at the proper time by means of the neck 7 which is so placed and of such a length that when the piston is at or near the end of its forward stroke, as shown 70 in Fig. 2, fluid passes from the passage 8 past the neck 7 and through port 10 and passage 11 to the forward end of bore 2. The exhaust of fluid from the opposite sides of the piston is shown in Fig. 1 to be accomplished 75 by a port 12 which leads to atmosphere from the central portion of the bore 2, and is uncovered by the piston at each end of the piston stroke, allowing escape of fluid alternately from the two sides of the piston.

In the form shown in Fig. 2, exhaust takes place through ports 13 and 14 in the ends of the bore 2 and is controlled by a valve 15, this exhaust arrangement forming no part of the present invention, but being fully described in the co-pending application of F. M. Slater, Serial No. 879,860 filed December 31, 1914.

The operation of the tool will be obvious from the above description. When the piston is in the position shown in Fig. 1 fluid will be admitted through passage 8 and past the neck 6 to the rear end of bore 2 and also to the rear end of bore 3 through the passage 9, thus exerting a forward pressure on 90 the rear face of the piston head 4 and the rear face of the shank 5. At the same time, the forward end of the bore 3 will be open to exhaust, either through the port 12 as shown in Fig. 1, or the ports 12 and 14 in 95 the form shown in Fig. 2. The piston will then move forward, the admission of fluid to the rear surfaces of the piston being cut off when the rear end of neck 6 passes beyond the forward edge of the passage 8. 100 After this point is reached the piston will move forward through the expansion of the admitted fluid until the rear face of the piston head passes the port 12, when the fluid of the rear ends of bores 2 and 3 will be ex- 105 110

hausted to atmosphere. At the same time this exhaust is taking place, the neck 7 will open communication between the passage 8 and the port 10 and passage 11 admitting fluid to the forward end of bore 3, and driving the piston rearwardly, whereupon the above described cycle of operations will be repeated.

It will be seen that by controlling the admission to the ends of the cylinder by the shank 5 which can be of comparatively small diameter, and admitting fluid also to the end of the smaller bore to exert pressure on the end of the shank 5, the full rear pressure surface of the piston is utilized, and at the same time the weight of the piston and the opportunity for leakage is greatly lessened, as compared with tools of the type shown in the Keller patent, mentioned above.

It is to be understood that while the present showing and description discloses certain specified modifications of the invention, other forms and modifications are included within the spirit and scope of the same, as expressed in the claims.

What I claim is:

1. In a fluid operated percussive tool, a cylinder having a bore of two diameters and a piston having a head fitting the larger portion of said bore and a shank fitting the smaller portion of said bore, and means for intermittently admitting fluid, to accomplish the stroke of the piston in the forward direction by exerting pressure on the end surface of said shank and the corresponding surface of said head and for intermittently exerting fluid pressure only on the surface of said head opposed to the two first mentioned surfaces to accomplish the stroke of the piston in the other direction.

2. In a fluid operated percussive tool, a cylinder, having a bore of two diameters, a piston having a head fitting the larger portion of said bore and a shank fitting the smaller portion of said bore, and passages controlled by said shank for directly admitting fluid pressure alternately to the face of said shank and the corresponding face of said head and to the opposite face of said head.

3. In a fluid operated percussive tool, a cylinder having a larger forward bore and a smaller rearward bore, a piston having a head fitting in said larger bore and a shank fitting in said smaller bore, and passages controlled by said shank for directly admitting pressure to the rear faces of said piston head and said shank near the rear end of the piston stroke, and to the forward face of said head near the forward end of said piston stroke.

4. In a fluid operated percussive tool, a cylinder having a larger forward bore and a smaller rearward bore, a head fitting said forward bore and a shank fitting said rear-

ward bore, a fluid inlet passage opening into the side of said smaller bore, and passages controlled by said shank for admitting fluid from said inlet passage at the same time to the rear ends of said bores near the rear end of the piston stroke, and for admitting fluid to the forward end of said larger bore near the forward end of the piston stroke.

5. In a fluid operated percussive tool, a cylinder having a larger forward bore and a smaller rearward bore, a piston having a head fitting said larger bore and a shank fitting said smaller bore, said shank having a plurality of depressions, a fluid conduit leading into the side of said smaller bore and ports and passages controlled by said depressions whereby fluid is admitted to said cylinder to exert pressure alternately on the entire rear surface of said piston, and on the forward surface of said piston head.

6. In a fluid operated percussive tool, a cylinder having a larger forward bore and a smaller rearward bore, a piston having a head fitting said larger bore and a shank fitting said smaller bore, and ports and passages controlled by said shank whereby fluid is directly admitted to said cylinder to exert pressure alternately on the entire rear surface of said piston and on the forward surface of said piston head.

7. In a fluid operated percussive tool, a cylinder having a larger forward bore and a smaller rearward bore, a piston having a head fitting said forward bore and a shank fitting said rearward bore, a passage connecting the rear ends of said bores, a fluid inlet passage controlled by said shank for intermittently conveying fluid to the rear ends of said bores, and means for intermittently conveying fluid to the forward end of said larger bore.

8. In a fluid operated percussive tool, a cylinder having a larger forward bore and a smaller rearward bore, a piston having a head fitting said larger bore, and a shank fitting said smaller bore, a fluid inlet passage controlled by said shank for conveying fluid to exert pressure intermittently on the entire rear surface of said piston and means for conveying fluid intermittently to exert pressure on the forward surface of said piston.

9. A percussive fluid motor comprising in combination a cylinder of two diameters, a piston therefor having an enlarged head and a relatively small head, said enlarged head presenting an intermediate pressure receiving area and an oppositely effective pressure receiving area and said small head presenting a third pressure receiving area, and valveless pressure fluid conduit means controlled by said piston providing a substantial period of pressure fluid expansion on each of said pressure receiving areas.

10. A percussive fluid motor comprising in combination a cylinder of two diameters, a piston therefor having an enlarged head and a relatively small head, said enlarged head presenting an intermediate pressure receiving area and an oppositely effective pressure receiving area and said small head presenting a third pressure receiving area, and valveless pressure fluid conduit means controlled by said piston providing a substantial period of pressure fluid expansion on said intermediate and third pressure receiving areas. 5
11. A percussive fluid motor comprising in combination, a cylinder of two diameters, a piston therefor having an enlarged head and a relatively small head, said enlarged head presenting an intermediate pressure receiving area and an oppositely effective pressure receiving area, said small head presenting a third pressure receiving area effective to move said piston in the same direction as said intermediate pressure receiving area, piston controlled pressure fluid admission means initially to admit pressure fluid both to said intermediate pressure receiving area and to said third pressure receiving area, and a piston controlled port for conducting pressure fluid from said admission means to said oppositely effective pressure area. 15
12. A percussive fluid motor comprising, in combination, a cylinder of two diameters, a piston movable therein having heads of different diameter, said cylinder and piston providing three pressure chambers large, small and intermediate; and piston controlled pressure fluid distributing conduit means providing initial admission of pressure fluid to said intermediate pressure chamber, and the admission of pressure fluid from said intermediate chamber to said small pressure chamber. 35
13. A percussive fluid motor comprising, in combination, a cylinder of two diameters; a piston movable therein having heads of different diameter, said cylinder and piston providing three pressure chambers large, small and intermediate; and piston controlled valveless pressure fluid distributing conduit means providing initial admission 40
- of live pressure fluid to a plurality of said chambers followed by a period of pressure fluid expansion in such chambers. 5
14. In a fluid operated percussive tool, a cylinder having a bore of two diameters, a piston having a head fitting the larger portion of said bore and a shank fitting the smaller portion of said bore, and passages controlled by said shank for admitting fluid pressure past said shank alternately to the face of said shank and the corresponding face of said head to the opposite face of said head. 60
15. In a fluid operated percussive tool, a cylinder having a bore of two diameters, a piston having a head fitting the larger portion of said bore and a shank fitting the smaller portion of said bore, and passages controlled by said shank for admitting fluid pressure through said passages alternately to the face of said shank and the corresponding face of said head to the opposite face of said head. 65
16. In a fluid operated percussive tool, a cylinder having a bore of two diameters, a piston having a head fitting the larger portion of said bore and a shank fitting the smaller portion of said bore, and passages controlled by said shank for admitting pressure past said shank to the rear face of said piston head and said shank near the rear end of the piston stroke and to the forward face of said head near the forward end of said piston stroke. 70
17. In a fluid operated percussive tool, a cylinder having a bore of two diameters, a piston having a head fitting the larger portion of said bore and a shank fitting the smaller portion of said bore, and passages controlled by said shank for admitting pressure through said passages to the rear face of said piston head and said shank near the rear end of the piston stroke and to the forward face of said head near the forward end of said piston stroke. 75
